UNITED STATES PATENT OFFICE.

GIULIO MARCHETTI, OF HALIFAX, COUNTY OF YORK, ENGLAND, ASSIGNOR
TO JOHN CROSSLEY & SONS, OF NEW YORK, N. Y.

DESIGN FOR A CHAIR-COVER.

SPECIFICATION forming part of Design No. 18,652, dated October 2, 1888.

Application filed September 6, 1888. Serial No. 284,765. Term of patent 3½ years.

To all whom it may concern:

Be it known that I, GIULIO MARCHETTI, a resident of Halifax, York county, England, have invented a certain new and original Design for Chair-Covers; and I do hereby declare the following to be a full, clear, and exact description of the same, such as will enable others skilled in the art to which it appertains to make and use the design, reference being had to the accompanying photograph, which forms part of this specification.

My invention relates to a design for chair-covers; and it consists in a novel ornamentation of the filling or body design of the cover and of the border surrounding the same, substantially as hereinafter described, and pointed out in the claim.

The accompanying photograph is a plan view of a chair-cover embodying my design.

A represents the filling or body design of the chair-cover, which filling is of eccentric Indian character. Figures B, C C C, and D represent trees, pines, and shrubs, with branches, leaves, and blossoms, conventional in treatment, and the whole resting upon a ground-work of small Indian ornament. Three bands, E F G, form the border surrounding said filling A. The filling of said bands is of scroll-work, Indian in character and harmonizing with the filling A.
